UNITED STATES PATENT OFFICE.

FRANKLIN B. GIESLER, OF MILWAUKEE, WISCONSIN.

WATER-METER.

SPECIFICATION forming part of Letters Patent No. 427,852, dated May 13, 1890.

Application filed June 6, 1889. Serial No. 313,329. (No model.)

To all whom it may concern:

Be it known that I, FRANKLIN B. GIESLER, of Milwaukee, in the county of Milwaukee, and in the State of Wisconsin, have invented certain new and useful Improvements in Water-Meters; and I do hereby declare that the following is a full, clear, and exact description thereof.

My invention relates to water-meters, and will be fully described hereinafter.

In the drawings, Figure 1 is a vertical longitudinal section of my device. Figs. 2 and 3 are details. Fig. 4 is a section on line 4 4, Fig. 1. Fig. 5 is a section on line 5 5, Fig. 1; and Fig. 15 6 is a detail.

A is a casing that incloses one end of a cylinder B, in which a piston C travels.

D is a valve-chamber, E a slide-valve, F an inlet-port, and G the outlet-port. A port a leads from the valve-chamber D to one end of the cylinder B, and b is a port that leads from the valve-chamber to the casing A, that opens into the inclosed end of cylinder B.

The stem D' of valve E passes through a boss c, in which is a bushing d, and, passing through the wall of casing A, is toggled by a link e to an arm f of a crank-lever g, that is loose on a shaft H, that is journaled in brackets I, that form part of the cylinder-casting.

The shaft H also carries another crank-lever M, and the hub M' of this lever, which is keyed or splined on shaft H, carries loosely on it the hubbed end h of a weighted lever j. The crank-lever g has two arms f' and f'', which are at approximately right angles to its arm f, and one of the arms f' carries a horizontal pin g' and the other f'' a like pin g'', which pins project into a plane drawn vertically through the length of lever j. Like pins m m' project from

40 crank-lever M into the same plane, and the pins on the two levers g and M just clear each other. The end of lever M farthest from its hub is toggled by a link N to the piston-head C, which travels in cylinder B, and the lever j is notched at j' j'' to receive the pins of levers

45 g and M during the action of the levers. The weight J of lever j is formed on its outer end with a lug J', having inclined sides and a flat top, and in the apex of case A is housed a sliding head A' and a spring A² for depressing it. The face of head A' is wedge-shaped, and projects normally through the wall of the casing,

and at stated periods in the operation of the meter intercepts the lug J' of lever j, as will be described farther on.

55

The operation of my device is as follows: Suppose the parts of my meter are in the position shown in Fig. 1. The inlet-pipe F is open to the meter, the outlet G closed from the inlet. Now, if the pipe G be opened, the pressure of the water in casing A will force the piston-head into cylinder B and expel the water

60

through port a and outlet G, and as the piston C advances the outer end of lever M is drawn down by toggle-lever N, and by the time the piston C reaches the limit of its stroke the pin m of lever M lifts the lever j and carries the flat portion of its lug J' under and beyond the point of head A', which, acting as a wedge,

65

gives an impulse to lever j to throw it over the center and down on the other side with sufficient force to enable it, when it falls on pin g² of lever g, to slide valve E by rocking lever g, and this sliding of valve E closes port b from

70

inlet F and opens it to outlet G, and closes port a from the outlet and opens it to the inlet, and the water-pressure in a forcing back piston C will reversely repeat the operation just described, thus causing the lever M to rock the shaft H every time the cylinder B is filled and

75

emptied; and that the rocking of this shaft may register the amount of water used I connect it with gearing by a spindle p, the inner end of which is flattened and projects into a slot p' in the adjacent end of shaft H, the slot

80

85 permitting the spindle to find the center of shaft H as it revolves. On its outer end spindle p may be connected with any desired form of registering-gear P.

85

The weight J is supported, when in the position shown in full lines, Fig. 1, by the upper wall of the cylinder, and when the piston is in the position shown in dotted lines by a shelf K.

90

R are cushions for the piston, and S are 95 drain-openings, which may be closed in any suitable manner.

Having thus described my invention, what I claim as new, and desire to secure by Letters Patent, is—

100

1. In a water-meter, a horizontal cylinder, a valve-chamber mounted thereon, a circular casing inclosing one end of said cylinder, and ports communicating from the valve-casing

- with the interior of the circular casing and with the opposite end of the cylinder, in combination with a rock-shaft mounted horizontally in said circular casing, a pair of T-shaped 5 toggle-levers mounted on said shaft, and connected, respectively, with the piston in the cylinder and the slide-valve in the valve-easing, and a weighted lever arranged to move radially about said shaft, and actuated by 10 studs on the T-lever, which is connected with the piston and engaging studs on the lever, which is connected with the slide-valve to move the same, substantially as described.
2. The combination, with a horizontal cylinder and a circular casing inclosing one end of said cylinder, of a weighted lever arranged 15 to oscillate within said circular casing, a

bracket within said casing forming a stop to limit the movement of the lever in one direction, the intruding end of the cylinder forming the stop or rest for the opposite throw of the lever, and a wedge-shaped spring-head or abutment mounted in the casing and engaging the wedge-shaped head of the lever to carry the same beyond its center, substantially as set forth.

In testimony that I claim the foregoing I have hereunto set my hand, at Milwaukee, in the county of Milwaukee and State of Wisconsin, in the presence of two witnesses.

FRANKLIN B. GIESLER.
